WATERPROOF CASE FOR A PHOTOGRAPHIC CAMERA

Nobuki Matsumoto, Sadao Okada, Masayuki Sakuma,
Ohiko Yagi, and Masatoshi Hidemitsu, Tokyo, Japan,
assignors to Kabushiki-Kaisha Ricoh, Tokyo, Japan

Filed Mar. 31, 1970, Ser. No. 22,138

Claims priority, application Japan Feb. 5, 1970

Term of patent 7 years

Int. Cl. D16—07

U.S. Cl. D61—1

FIG. 1

FIG. 2

FIG. 3

FIG. 1 is a front, top and left side perspective view of a waterproof case for a photographic camera, showing our new design;

FIG. 2 is a rear, top and right side perspective view; and

FIG. 3 is a sectional view through a vertical plane passing through the nominal optical axis of the said waterproof case, showing in FIG. 1.

Portions of the figures of the drawing are diagonally lined to indicate transparency.

We claim:

The ornamental design for a waterproof case for a photographic camera, substantially as shown and as
